UNITED STATES PATENT OFFICE.

WALLACE C. CLARK, OF NEW YORK, N. Y.

DESIGN FOR A FEED-PIPE FOR INHALATION APPARATUS.

SPECIFICATION forming part of Design No. 32,480, dated April 10, 1900.

Application filed February 24, 1900. Serial No. 6,423. Term of patent 7 years.

To all whom it may concern:

Be it known that I, WALLACE C. CLARK, a citizen of the United States, residing at New York, in the county of New York and State of New York, have invented and produced a new and original Design for a Feed-Pipe for Inhalation Apparatus, of which the following is a specification, reference being had to the accompanying drawings, forming part thereof.

10 Figure 1 is a plan view. Fig. 2 is a side elevation. Fig. 3 is an end elevation.

As shown in the drawings, the leading and natural feature of my design relates to an arrangement and configuration of a feed-pipe for inhalation apparatus; and it consists of a frame formed of perforated sides 1 and end pieces 2 and 3, the end piece 3 being upon a lower plane than the end piece 2 and joined to the sides by depending sections 4. Projecting from the end piece at a point central 20 of its length is a section 5, which projects in

parallelism with the sides 1, but on a different plane. The parts just described are all joined in cross-section and describe an oblong figure with a projecting end when viewed in plan and a substantially-rectangular figure when viewed in front elevation, the whole presenting a compact and finished appearance.

Having described my invention, what I claim as new, and desire to secure by Letters Patent, is—

The design for a feed-pipe for inhalation apparatus as herein shown and described.

In testimony whereof I have signed my name to this specification in the presence of two subscribing witnesses.

WALLACE C. CLARK.
